DESIGN FOR A BURIAL VAULT

Robert E. Butler, La Crosse, Wis.

Application May 11, 1945, Serial No. 119,492

Term of patent 14 years

(Cl. D19—1)

To all whom it may concern:

Be it known that I, Robert E. Butler, a citizen of the United States of America, residing in La Crosse, in the county of La Crosse and State of Wisconsin, have invented a new, original, and ornamental Design for a Burial Vault, of which the following is a specification, reference being had to the accompanying drawing, forming part thereof, in which:

Figure 1 is a top plan view of a burial vault, showing my new design;

Figure 2 is a side elevational view thereof; and Figure 3 is an end view of the burial vault.

I claim:

The ornamental design for a burial vault, as shown.

ROBERT E. BUTLER.
